UNITED STATES PATENT OFFICE.

JOHN E. McMINN, OF LOUISVILLE, KENTUCKY, ASSIGNOR TO PEERLESS MANUFACTURING COMPANY, OF LOUISVILLE, KENTUCKY, A CORPORATION OF KENTUCKY.

COAL CHUTE.

Application filed September 28, 1923. Serial No. 665,484.

To all whom it may concern:

Be it known that I, JOHN E. McMINN, a citizen of the United States, residing at Louisville, in the county of Jefferson and 5 State of Kentucky, have invented a certain new and useful Improvement in Coal Chutes, of which the following is a full, clear, and exact description, reference being had to the accompanying drawings.

10 My present invention relates to improvements in that class of devices known as coal chutes that are designed to be set into a foundation or other wall of a building and through which coal or other material may 15 be passed into the building, as into the basement or coal room.

The general objects of the invention are to provide a comparatively simple and inexpensive device of the aforesaid character 20 that presents a neat appearance when built into a wall, is very substantial and durable, and is particularly convenient of operation when it is desired to open the chute for the reception of material, or close it after the 25 material has been discharged through the chute.

Further objects are to provide a chute of the class referred to that is equipped with a door having a pane of glass or other trans- 30 parent or translucent material so that light may be admitted through the chute when the door is closed, and which door is adapted to be retracted into the chute in such a position that the pane is not liable to be- 35 come broken through being struck by ma- terial passed through the chute; to provide latch mechanism for locking the door in closed position from inside and which is ar- ranged to be released from a distant point 40 when it is desired to open the door; to so balance the door that upon the release of the latch the door will swing ajar so that a per- son on the outside of the building may move the door to its full open position; to provide, 45 in a device of the character referred to, a chute extension or hopper that is movably connected to the chute in such a way that it may be drawn out of the chute for use and held there by suitable means or released and 50 moved into the chute when not in use; to provide a mounting for said chute extension or hopper involving a part that is engaged by the door as the door approaches closed 55 position and through the intervention of which the door when closed returns the

chute extension or hopper to its fully re- tracted or normal position within the chute.

The objects above set forth, with others hereinafter appearing, are attained in the construction illustrated in the accompany- 60 ing drawings wherein Fig. 1 is a front elevation; Fig. 2 a rear elevation and Fig. 3 an end elevation of my improved chute; Fig. 4 is a vertical section through the chute on the line 4—4 of Fig. 2, looking in the direc- 65 tion of the arrows; and Fig. 5 is a view similar to Fig. 4 showing the door of the chute open and the chute extension or hopper extended in receiving position.

The chute proper is in the nature of a box 70 like casing made up of integral top and end walls 1 and 2, respectively, and a bottom wall 3 that is provided with flanges 4 at its ends which, as shown in Fig. 2, overlap the outer sides of the lower edges of the end 75 walls 2 and are secured thereto by suitable means. Applied to the front of this structure is an open rectangular frame 6 of neat design and shown as having a peripheral flange 7. A lip 8 projects from the inner 80 or rear side of the frame adjacent the edge of its opening, and the front edges of the top wall 1, end walls 2, and bottom wall 3 are secured to enlargements or bosses 9 of the lip by bolts 10, or their equivalents. 85

Extending along the bottom side and each end of the frame are shoulders 12 which cor- 90 respond to the stops in ordinary door struc- tures, and for that reason I shall refer to said parts hereinafter as stops. The top 95 ends of the end stops 12 are enlarged some- what and extended inwardly, as best seen in Figs. 1 and 2, the enlargement of one of the stops being revealed in the former view where the door is broken away. Guides 13, which in the present instance are in the na- 100 ture of angle bars, extend horizontally along the end walls 2 and may be secured to said walls by any suitable means; and the top surfaces of the guides 13 are substantially flush with the upper ends of the stops 12. Directly in front of the guides 13, the front frame 6 is provided with hollow enlargements providing pockets 15 that open out- 105 side the frame through the sides of the en- largements, for a purpose which shall pres- ently appear.

The door is designated 18 and in the pres- 110 ent embodiment it has an opening 19 that is closed by a glass pane 20 held in place by

a lip 21 and screws or the like 22. Projecting endwise from the top of the door and offset forwardly from the front plane thereof, are trunnions 24 which, when the door 5 is closed, repose within the pockets 15, entering the same through the openings in the sides thereof. This construction effects a hinge like connection between the door and frame, and the door is adapted to be swung 10 from a vertical to a horizontal position upon the trunnions. When in the latter position, it may be slid rearwardly along the guides 13 into the position shown in Fig. 5 where it will be out of the way and protected 15 against breakage of the pane 20 when coal or other material is passed through the chute.

Pivoted upon a bolt or pintle 26, that is supported by and between lugs 27 which 20 project rearwardly from the lower edge of the door, is a latch plate 28 having a nose 29 that is arranged to engage over a keeper 30 shown as formed integral with the frame 6. A flexible element or chain 32 has one 25 of its ends connected to the latch plate 28 and is led therefrom, through a guide 33 at the top of the door and an eye 34 that is carried by the top wall 1 near its rear edge, to a point within the building where it may 30 be conveniently pulled for the purpose of releasing the latch. The guide 33 is shown as formed by a pin or bolt 35 that extends through spaced lugs 36 which project inwardly and upwardly from the top edge of 35 the door.

To facilitate dumping or shoveling coal or other material through the chute, I provide a chute extension or hopper 40 which is swung at its forward edge from the frame 40 6 through links 41. The lower ends of the links are pivotally connected, through rivets 42 or the like, to the end walls of the hopper and the upper ends of the links are similarly connected, through bolts 43 or the like, 45 to lugs 44 which extend inwardly from the stops 12. Abutments 45 are applied to the bottom of the hopper for engagement over the bottom door stop to hold the hopper in extended position, as illustrated in Fig. 5.

With my improved chute constructed and installed as described, when it is desired to open the chute the flexible element or chain 32 is pulled to release the latch plate 28 from the keeper 30 whereupon the door, by 50 reason of the manner in which it is balanced, and the further fact that it is forced outwardly somewhat by the weight of the hopper 40 transmitted thereto through the links 41, swings to the dotted line position 55 shown in Fig. 4. The door may then be swung to a horizontal position and slid in along the guides 13 to a position shown in Fig. 5 after which the hopper may be withdrawn from the chute and held in extended 60 position by the abutments 45, as above ex-

plained. After the coal or other material has been passed through the chute, the abutments 45 may be released from the stop 12, as by striking the hopper from underneath with a shovel and the hopper, pushed back 70 into the chute and the door 18 withdrawn from the guides 13 to lodge the pintles 24 within the pockets 15 after which the door may be allowed to swing downwardly to closed position, and upon its being fully 75 closed the nose 29 of the latch plate 28 will reengage the keeper 30 and retain the door in closed position.

Having thus described my invention, 80 what I claim is:

1. In a device of the character set forth, the combination of a chute, a door which when in a vertical position is arranged to close the chute, connections between the door and chute permitting the door to be swung from a vertical to a horizontal position and then slid into the chute, a latch carried by the edge of the door for locking engagement with a part of the chute when the door is in closed position, and a flexible element having connection with the latch and extending through suitable guides to a remote point from which the latch may be released by a pull upon the flexible element. 85

2. In a device of the character set forth, the combination of a chute, a door which when in a vertical position is arranged to close the chute, connections between the door and chute permitting the door to be swung from a vertical to a horizontal position and then slid into the chute, a latch carried by the edge of the door for locking engagement with a part of the chute when the door is in closed position, and a flexible element having connection with the latch and extending through a guide on the door and through a guide on the top of the chute to a remote point from which the latch may be actuated by a pull upon the flexible element, the guides retaining said element in close proximity to the door when the latter is open. 90

3. In a device of the character set forth, the combination of a chute comprised of top, bottom and end walls, an open frame secured to the front of the chute, a door for closing the opening in the frame, the frame having pockets at the ends of the top of said opening, guides carried by the end walls of the chute and extending rearwardly from said pockets, the door having trunnions which occupy the aforesaid pockets when the door is in closed position, the door being adapted to be swung from closed position to open position and slid into the chute upon 105 said guides. 115

4. In a device of the character set forth, the combination of a chute comprised of top, bottom and end walls, an open frame applied to the front of the chute, a door for 120 125 130

- closing the opening in the frame, the frame having pockets adjacent the ends of the top of said opening, guides carried by the end walls of the chute and extending rearwardly 5 from said pockets, the door having trunnions which occupy the pockets when the door is in closed position, a latch plate pivotally connected to the inner side of the door adjacent its lower edge which is arranged to 10 interlock with a keeper on the frame, a guide in substantially vertical alignment with the latch and carried by the top edge of the door, and a flexible element connected to the latch plate and extended through said 15 guides to a remote point from where the latch may be released by a pull exerted upon the flexible element.
5. In a device of the character set forth, the combination of a chute comprised of top, 20 bottom and end walls, an open frame applied to the front of the chute, a door for closing the opening in the frame, the frame having pockets adjacent the ends of the top of said opening, guides carried by the end 25 walls of the chute and extending rearwardly from said pockets, the door having trunnions which occupy the pockets when the door is in closed position, a latch plate pivotally connected to the inner side of the door adjacent its lower edge which is arranged to 30 interlock with a keeper on the frame, a guide in substantially vertical alignment with the latch and carried by the top edge of the door, a second guide carried by the 35 top wall of the chute, and a flexible element connected to the latch plate and extended through said guides to a remote point from where the latch may be released by a pull exerted upon the flexible element.
- 40 6. In a device of the character set forth, the combination of a chute, a door for closing the front of the chute and having such connection therewith as will permit the door to be swung from closed position to a substantially horizontal open position and slid 45 into the chute, a hopper, links connecting the front portion of the hopper with the front of the chute so that said hopper may be swung from a position inside the chute to 50 a position wherein it projects from the chute, means carried by the hopper for co-

operation with a part of the chute for holding the hopper in the latter position, the hopper, when said means is released, tending to swing to a position within the chute, 55 the aforesaid links being arranged to be engaged by the door during the closing of the latter so as to move the hopper further into the chute.

7. In a device of the character set forth, 60 the combination of a chute, a door for closing the front of the chute and connected with the chute so as to be swung from closed position to open position and slid into the chute, a hopper, links connecting 65 the lower front portion of the hopper to the upper front portion of the chute whereby the hopper may be moved from a position within the chute to a second position wherein the hopper projects partially out through 70 the front of the chute, the hopper having parts interengaging with parts of the chute for maintaining the hopper in its outer position.

8. In a device of the character set forth, 75 the combination of a chute comprising top, bottom and end walls, guides supported in opposed relation to each other by the end walls of the chute and having pockets adjacent the forward ends of the guides, a 80 door arranged to close the mouth of the chute and having trunnions reposing within said pockets and whereon the door is adapted to swing from closed to open position and slid along said guides to a position within 85 the chute, a hopper comprised of bottom and end walls, links arranged one at each end of the hopper, means pivotally connecting the lower ends of the links to the lower front corners of the end walls of the hopper, 90 further means similarly connecting the upper ends of the links to portions of the chute, the hopper being movable from a position inside the chute to a position wherein the hopper projects out through the 95 front of the chute, and means carried by the bottom wall of the hopper for cooperation with the bottom portion of the chute for holding the hopper in its outer position.

In testimony whereof, I hereunto affix my 100 signature.

JOHN E. McMINN.
